DESIGN FOR A BOTTLE

Israel Myer, New York, N. Y., assignor to Myer
Products, Inc., New York, N. Y., a corporation of New York

Application September 13, 1935, Serial No. 58,549

Term of patent 14 years

To all whom it may concern:

Be it known that I, Israel Myer, a citizen of the United States, residing at New York, in the county of New York and State of New York, have invented a new, original, and ornamental Design for a Bottle, of which the following is a specification, reference being had to the accompanying drawing, forming part thereof.

The single figure is an elevational view of a bottle, showing my new design.

The bottle has the same appearance on all sides as that disclosed in the elevational view.

I claim:

The ornamental design for a bottle, as shown and described.

ISRAEL MYER.
